UNITED STATES PATENT OFFICE

106,406

DESIGN FOR A TEXTILE FABRIC

Jacques Heim, Paris, France

Application July 1, 1937, Serial No. 70,189

Term of patent 3½ years

To all whom it may concern:

Be it known that I, Jacques Heim, a citizen of France, residing at Paris, 15 Avenue Matignon Department of Seine, have invented a new, original, and ornamental Design for a Textile Fabric, of which the following is a specification, reference being had to the accompanying drawing, forming part thereof, wherein,

The figure is a plan view of a piece of textile fabric showing my new design.

The upper and lower edges selvedge, and the design repeats horizontally.

The design consists in the specific arrangement of stripes each of which differs from the adjoining one both as to width and color throughout the entire width of the fabric, as shown.

I claim:

The ornamental design for a textile fabric substantially as shown and described.

JACQUES HEIM.
